UNITED STATES PATENT OFFICE.

EDWARD G. HODGES, OF MARSHALLTOWN, IOWA.

CARBURETER.

1,330,024.

Specification of Letters Patent.

Patented Feb. 3, 1920.

Application filed July 3, 1918. Serial No. 243,192.

To all whom it may concern:

Be it known that I, EDWARD G. HODGES, a citizen of the United States, and resident of Marshalltown, in the county of 5 Marshall and State of Iowa, have invented a certain new and useful Carbureter, of which the following is a specification.

The object of my invention is to provide a carbureter for internal combustion engines 10 of the type in which the air supply is regulated and controlled according to the speed of the engine directly, rather than by suction from the engine.

More particularly it is my object to provide such a carbureter having an air supply pipe or passage and having an auxiliary air supply pipe or passage, and having some mechanism whereby the passage of air through said respective passages may be 20 regulated according to the engine's speed.

With these and other objects, which will appear later herein, in view my invention consists in the construction, arrangement and combination of the various parts of the 25 device whereby the objects contemplated are attained, as hereinafter more fully set forth, pointed out in my claims and illustrated in the accompanying drawings, in which:

The figure shows a side elevation partly 30 in vertical section of a carbureter embodying my invention, and equipped with air valves and with controlling mechanism therefor, including a governor device adapted to be operatively connected with a moving part of an engine.

My improved carbureter is intended for motor vehicle engines or any explosive engine that has a manually controlled throttle and operated under a variation in load and 40 speed. I will describe it as used with an ordinary vehicle engine.

In the accompanying drawing I have used the reference numeral 10 to indicate generally a hollow shell, the upper portion of 45 which forms a mixing chamber of the carbureter.

Adjacent to the carbureter shell 10 is an ordinary float chamber 11 to which fuel is supplied by means of the tube 12. In the 50 carbureter casing 10 is an ordinary fuel nozzle 13, and an ordinary needle valve 14.

is provided for regulating the discharge of fuel from the nozzle 13. It will be understood, of course, that the nozzle 13 communicates with the float chamber or fuel supply. 55

The interior of the carbureter casing 10 adjacent to the discharge end of the nozzle 13 preferably has the Venturi tube shape.

Communicating with the lower portion of the carbureter casing 10 is an ordinary air 60 passage or tube 15. Spaced above the discharge nozzle 13 is a throttle valve 16 which may be operated from the dash or otherwise in an suitable way.

Above the throttle valve 16 is a fuel mixture passage 17 for conducting the fuel mixture to the intake manifold to the engine cylinders. 65

Communicating with the fuel mixture passage 17 is an auxiliary air tube or passage 18. 70

In the tube 15 is substantially mounted a butterfly valve 19 forming a choke valve.

When the valve 19 is in its ordinary closed or normal position it is extended directly 75 across the tube 15. In the tube 18 is another butterfly valve 20 adapted to coact with a seat 21 and so arranged that when seated it is extended diagonally across the interior of the tube 18.

On the stem 22 of the valve 19 is an arm 23, and on the stem 24 of the valve 20 is an arm 25. 80

Preferably formed integral with the upper portion of the fuel mixture passage 85 17 is a bracket 26 on which is formed a bearing 27 for an upright governor shaft 28. The upright shaft 28 is designed to be connected by a flexible shaft 29 with a substantially moving part of the engine on which 90 the carbureter is used.

Above the bearing 27 there is fixed to the shaft 28 a collar 30 to which are pivoted opposite upwardly extending arms 31 which are secured to the balls 32 of the governor 95 device.

Spaced above the balls 32 is a collar 33 slidably mounted on the shaft 28 and connected with the balls 32 by links 34.

On the collar 33 is formed a grooved hub 100 or the like 35. On the fuel supply passage 17 is another bracket or arm 36 on which

is centrally pivoted a bell crank lever 37. One end of the bell crank lever 37 extends into the groove of the hub 35, as illustrated in the drawing.

6 Pivoted to the other end of the bell crank lever 36 is a link 38 which extends toward and is pivoted to the arm 25 of the valve stem 24 by means of a pin or the like 39.

The link 38 has a series of openings 40 for selectively receiving the pin 39.

10 The arm 25 also has a series of openings 41 for receiving said pin 39. By selectively mounting the pin 39 in different openings 40 and 41 the relative movement of the arm 15 25 and the valve 20 with relation to the governor may be adjusted and regulated.

15 Pivoted in the pin 39 is a link 20 42 which is also pivotally connected with the arm 25 by means of a pin 43 selectively mounted in one of a plurality of holes 44 in the link 42. It will be seen that by selectively mounting the pin 43 in different holes 44 and by the adjustment of the pin 39 above referred to, the relative movement 25 of the valve 19 with relation to the governor device may be regulated, and the relative movement of the valves 20 and 19 with relation to each other may be regulated as desired.

20 A portion of the shaft 28 just above the collar 30 is screw-threaded at 45 and on said screw-threaded portions are lock nuts 46. Between the upper nut 46 and the collar 33 is a spring 47 which normally tends to hold 35 the collar 33 in its raised position for thereby holding the bell crank lever 37 in such position as to close the valves 20 and 19.

25 In the practical operation of my improved carbureter the carbureter is installed on the 40 engine in the ordinary way and the tube 12 is connected with a suitable source of fuel supply.

The flexible shaft 29 is operatively connected with some moving part of the engine.

30 45 The fuel mixture passage 17 is connected with the intake manifold, and the device is then ready for use.

35 In such practical use of my improved carbureter, the parts are originally so set that the valves 19 and 20 will normally be held in their closed position as illustrated in the drawing.

The position of the valves just described is that which they should assume when the 40 engine is being started or is run at low speed.

45 As the speed of the engine increases the balls 32 will tend to be thrown outwardly by centrifugal force and draw the collar 43 downwardly, thereby controlling the bell 50 crank lever 37 for moving the links 38 and 42 for opening the valves 20 and 19.

55 It will be noted that the arm 28 is shorter than the arm 25, so that the opening movement of the valve 19 is more rapid than the opening movement of the valve 20.

It may be mentioned in this connection that the valve 19 is of such size as to allow the passage of a certain amount of air even when the valve 19 is in its closed position, shown in the drawings, so that sufficient air 70 is admitted to the carbureter for starting and running at very slow speed.

In the description and drawings I show an ordinary centrifugal or ball governor. Any other style of governor may be used 75 that will operate the air valves according to the speed of the engine.

Flexible air tubes or the like may be connected to the air intakes to carbureter and extended to a stove or exhaust manifold or 80 to any other part of the motor for picking up hot air or vapors.

As the engine reaches high speed, a great deal of air is supplied through the auxiliary air supply tube 18, so that even though the 85 suction from the engine becomes very great the volume of the mixture supplied to the engine remains substantially constant.

It will be seen that this is possible with my device because even though the throttle 90 valve is closed a proper amount of air for maintaining a volume can be secured through the tube 18.

It is well-known that when the engine is traveling at high speed with partly closed 95 throttle the richness of the mixture may be reduced without lessening the efficiency of the engine, and it is obvious that such a reduction is accomplished with my device.

When it is desired to increase the speed 100 or for any reason more load is required on the engine, the throttle valve will be moved toward open position and allow more air to be drawn through the tube 15 and past the fuel nozzle and thereby increase the richness 105 of the mixture in proportion to the load on the engine.

It will, of course be obvious that ordinarily when the load on the engine reduces the speed thereof, the driver will open the 110 throttle valve 16 whereupon the relative amount of air drawn through the tube 15 will be increased, and such air passing by the fuel nozzle will pick up the fuel and increase the richness of the mixture for the 115 load on the engine.

In the course of extensive experiments with various forms of carbureters and auxiliary air devices, I have found that better results can be secured with a device of the 120 type herein described, in which all of the air supplied to the fuel mixture is controlled according to the speed of the engine in some positive manner.

I have found, however, that the positive 125 control of the air valves according to the speed of the engine procures better results than the control of said valves by the suction from the engine.

It will be noted that in a device of this 130

kind when the engine is working up speed and the throttle is open, air will be drawn through the tube 15 past the fuel nozzle for securing a proper rich mixture, but when the 5 engine has reached the desired speed and the driver moves the throttle 16 toward closed position, the amount of air drawn through the tube 15 will be reduced, but considerable air will be drawn through the 10 tube 18 into the fuel mixture, whereby the fuel mixture will be thinned, but the total volume will be properly maintained.

Such a construction has numerous advantages.

15 As a matter of fact the parts of my device are preferably so arranged that when the throttle is closed, very little or no air is drawn through the tube 15 and past the fuel nozzle, so that if the engine may be traveling 20 at a high speed with the throttle closed a volume of air only is drawn into the engine through the tube 18.

While the engine is traveling at very slow speed with maximum load the only air admitted to the carburetor is what will suck past the valve 19 while it is in position shown in the drawing.

It will be seen that by properly adjusting the controlling levers and arms connected 30 to the air valves, and having the right adjustment to the fuel nozzle, it will be impossible for the engine to load up with fuel, or to overload and choke with either air or fuel when the throttle is opened very suddenly.

It will also be seen that by furnishing the proper mixture at all times and preventing overloading of the engine with fuel and oil from the crank case, the formation of carbon 40 in the combustion chamber will be almost entirely eliminated, and at the same time there will be effected a big saving in fuel and cylinder oil.

It will be noted that with this style of carburetor there will be no adjusting of any kind after the valves have been adjusted to right relation with the governor device, and the controlling levers and arms connected to the valves are adjusted so the valves will 50 operate in the proper relation to each other, and the fuel nozzle opening is made the proper size for the motor used. No dash control of any kind is necessary except to operate the throttle valve. The driver will 55 operate the throttle according to the load on the engine and speed desired, and all else is automatically operated and controlled by the governor device.

With such a structure there is not the 60 tendency to suck fuel into the engine when it is not needed that would otherwise be the case, for the reason that sufficient air may be supplied through the tube 18, while drifting with closed throttle. Neither is there 65 the creation of such a vacuum in the cylinder

ders as to tend to draw an undue amount of oil into the cylinders from the crank case.

Thus when there is no load on the engine and the throttle is closed air only is supplied to the engine, and as the load increases the 70 throttle is opened and the amount of fuel is increased until the maximum richness of the fuel mixture is reached when the engine is carrying its maximum load.

I claim as my invention:

1. A carburetor designed for use with an internal combustion engine, comprising a mixture producing device including a manually controlled throttle valve, said device having means for supplying air to the fuel 80 before the resulting mixture is taken into the engine, automatically operated means for varying the proportion of air and fuel, comprising air passages communicating with said device on opposite sides of said 85 throttle valve, valves in said passages, a governor operatively connected with said last named valves for causing their simultaneous movement, for furnishing a lesser proportion of fuel and a greater proportion 90 of air when the speed of the engine increases, and for furnishing a greater proportion of fuel and a lesser proportion of air when the speed of the engine decreases.

2. A carburetor designed for use with an 95 internal combustion engine, comprising a mixture producing device, said device having means for supplying air to the fuel before the resulting mixture is taken into the engine, automatically operated means for 100 varying the proportion of air and fuel, for furnishing a lesser proportion of fuel and a greater proportion of air when the speed of the engine increases, and for furnishing a greater proportion of fuel and a lesser proportion of air when the speed of the engine decreases, said device including a manually operated throttle valve, the parts being so arranged that when the throttle valve is open a richer mixture is supplied, and when 110 the throttle valve is moved toward closed position a leaner mixture is supplied.

3. A carburetor designed for use with an internal combustion engine, comprising a mixture producing device including a 115 manually operated throttle, said device having means for supplying air to the fuel before the resulting mixture is taken into the engine, automatically operated means for varying the proportion of air and fuel, comprising air passages communicating with said device on opposite sides of said throttle valve, valves in said passages, means for automatically operating said valves for giving them simultaneous, corresponding disproportionate movement, for furnishing a lesser proportion of fuel and a greater proportion of air when the speed of the engine increases, and for furnishing a greater proportion of fuel and a lesser proportion of 130

air when the speed of the engine decreases, said device including a governor designed to be operatively connected with a moving part of the engine and operatively connected with the air controlling means.

4. In a device of the class described, a carbureter or mixture producing device designed for use with an internal combustion engine having a fuel supply device and having a manually operated throttle valve, means for supplying air to the fuel, said means including a plurality of air supply passages, valves in said passages, and means for operatively connecting said valves with a moving part of the engine for controlling said valves for automatically increasing the relative proportion of air with relation to the fuel when the engine speed increases, and decreasing the proportion of air with relation to the fuel when the engine speed decreases, and for furnishing a substantially constant volume of air or fuel mixture for each engine charge.

5. A carbureter designed for use with internal combustion engines comprising a mixing chamber with a manually operated throttle valve therein, an air passage communicating with said chamber between the throttle valve and the discharge end of said chamber, a valve in said air passage, an air passage communicating with said chamber on the opposite side of said throttle valve, a fuel supply device in said chamber between said last air passage and said throttle valve, a valve in said last air passage, and means for automatically, simultaneously controlling said valves according to the speed of the engine and for furnishing a substantially constant volume of air or fuel mixture for each engine charge at all engine speeds and in all positions of the throttle valve.

6. A carbureter designed for use with internal combustion engines comprising a mixing chamber with a manually operated throttle valve therein, an air passage communicating with said chamber between the throttle valve and the discharge end of said chamber, a valve in said air passage, an air passage communicating with said chamber on the opposite side of said throttle valve, a fuel supply device in said chamber between said last air passage and said throttle valve, a valve in said last air passage, means for automatically, simultaneously actuating said valves according to the speed of the engine, so that said second and third valves are simultaneously, correspondingly operated, said third valve being arranged for more rapid movement than the second valve.

7. A carbureter designed for use with internal combustion engines comprising a mixing chamber with a manually operated throttle valve therein, an air passage com-

municating with said passage between the throttle valve and the discharge end of said chamber, a valve in said air passage, an air passage communicating with said chamber on the opposite side of said throttle valve, a fuel supply device in said chamber between said last air passage and said throttle valve, a valve in said last air passage, and a governor device operatively connected with both of said air passage valves for controlling said valves for correspondingly opening them when the engine speed increases, and effecting contrariwise movement of said valves when the speed of the engine decreases, said throttle valve being located so that it may be moved for controlling the flow of air from the second air passage past said fuel supply device.

8. A carbureter designed for use with internal combustion engines comprising a mixing chamber with a manually operated throttle valve therein, an air passage communicating with said passage between the throttle valve and the discharge end of said chamber, a valve in said air passage, an air passage communicating with said chamber on the opposite side of said throttle valve, a fuel supply device in said chamber between said last air passage and said throttle valve, a valve in said last air passage, means for automatically, simultaneously actuating said air passage valves according to the speed of the engine, so that said air passage valves are simultaneously, correspondingly operated, said device including adjustable means for varying the relative action of the valves in the air passages.

9. In a device of the class described, a carbureting chamber, a manually controlled throttle valve therein, an air supply passage communicating with said chamber between said throttle valve and the discharge end of said chamber, an air supply passage communicating with said chamber on the opposite side of said throttle valve, a fuel supply device between said last air supply passage and said throttle valve, valves in said passages, a governor device designed to be operatively connected with a moving part of the engine and connected with said air passage valves for giving them simultaneous, corresponding movement.

10. In a device of the class described, a carbureting chamber, a manually controlled throttle valve therein, an air supply passage communicating with said chamber between said throttle valve and the discharge end of said chamber, an air supply passage communicating with said chamber on the opposite side of said throttle valve, a fuel supply device between said last air supply passage and said throttle valve, valves in said passages, means for simultaneously, correspondingly, disproportionately actuating said valves, said means including a governor

device adapted to be connected with a moving part of the engine.

11. A carbureter or mixture producing device for an internal combustion engine comprising in combination a manually operated throttle valve, a mixing chamber having an air passage communicating therewith between said throttle valve and the discharge end of said chamber, a valve in said 5 air passage, a fuel supply means communicating with said chamber on the opposite side of said throttle valve from said air passage, a second air passage communicating with said chamber at such a point that 10 the air supply taken into the mixing chamber through the second air passage will pass the discharge point of said fuel supply device and pick up the fuel required for the mixture, and a governor device designed to 15 be operated from a moving part of the en- 20

gine, and operatively connected with the valves in said air passages.

12. In a device of the class described, a carbureter chamber, air supply passages communicating with said chamber, a fuel 25 supply device in said chamber between the points of communication between the chamber and the air supply passages, valves in said passages, means for simultaneously, correspondingly, disproportionately actuating said valves, substantially according to the speed of an engine, and a throttle valve arranged between said fuel supply device and the air supply passage nearest the discharge end of the carbureter chamber, and 30 means capable of actuation independently of said other valves.

Des Moines, Iowa.
